Primary Examiner — Thomas Johannes*Assistant Examiner* — Shawn T Gingrich(74) *Attorney, Agent, or Firm* — Whyte Hirschboeck Dudek S.C.(57) **CLAIM**

The ornamental design for corner connector for a photovoltaic module frame, as shown and described.

DESCRIPTION

FIG. 1 is a perspective view of a corner connector for a photovoltaic module frame showing our new design;

FIG. 2 is a top plan view thereof;

FIG. 3 is a front elevation view thereof;

FIG. 4 is a rear elevation view thereof;

FIG. 5 is a right side elevation view thereof;

FIG. 6 is a left side elevation view thereof; and,

FIG. 7 is a bottom plan view thereof.
